US0D1041249S

(12) **United States Design Patent** (10) Patent No.: **US D1,041,249 S**
(45) Date of Patent: ** Sep. 10, 2024

(54) **DISPENSER BASE**

(71) Applicant: **Brio Water Technology, Inc.**, City of Industry, CA (US)

(72) Inventors: **Arman Melkonian**, La Cañada Flintridge, CA (US); **Mark Melkonian**, Northridge, CA (US); **Lance Hussey**, Simi Valley, CA (US); **Joshua Probst**, Culver City, CA (US); **Craig Steele**, Manhattan Beach, CA (US); **Cary Chow**, Santa Monica, CA (US); **Ravi Sawhney**, Malibu, CA (US)

(73) Assignee: **Brio Water Technology, Inc.**, City of Industry, CA (US)

(**) Term: **15 Years**

(21) Appl. No.: **29/930,792**

(22) Filed: **Mar. 2, 2024**

(51) LOC (14) Cl. **07-06**

(52) U.S. Cl.

USPC **D7/397**

(57) **CLAIM**

We claim the ornamental design for a dispenser base, as shown and described.

DESCRIPTION

FIG. 1 is a front, top perspective view, showing our new design for a dispenser base;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front, top perspective view of a dispenser, showing our new design for a dispenser base in use with a dispenser; and,

FIG. 9 is a front, bottom perspective view of a dispenser, showing our new design for a dispenser base in use with a dispenser.

The broken lines show portions of the dispenser that form no part of the claimed design.

1 Claim, 7 Drawing Sheets
